(57) **CLAIM**

The ornamental design for a top for an appliance, as shown and described.

DESCRIPTION

FIG. 1 is a perspective view of a top for an appliance showing our new design.

FIG. 2 is a front view of a top for an appliance.

FIG. 3 is a side view of a top for an appliance.

FIG. 4 is another side view of a top for an appliance; and, FIG. 5 is a top view of a top for an appliance.

The broken line showing of a washing machine cabinet in FIGS. 1-5 is included for the purpose of showing environmental portions of the top for an appliance and forms no part of the claimed design.

1 Claim, 5 Drawing Sheets

FIG. 1

FIG. 2

FIG. 3

FIG. 4

FIG. 5
